C. J. KELLOWAY

RAILWAY SWITCH OPERATING MEANS

Filed Jan. 22, 1923

INVENTOR:
C. J. Kelloway,
BY
A. Z. Vencill
Attorney

UNITED STATES PATENT OFFICE.

CHARLES J. KELLOWAY, OF WILMINGTON, NORTH CAROLINA.

RAILWAY-SWITCH-OPERATING MEANS.

Application filed January 22, 1923. Serial No. 614,200.

To all whom it may concern:

Be it known that I, CHARLES J. KELLOWAY, a citizen of the United States, residing at Wilmington, in the county of New Hanover and State of North Carolina, have invented certain new and useful Improvements in Railway-Switch-Operating Means, of which the following is a specification.

My invention relates to means for operating the movable points of railway switches, and has for an object the provision of means for eliminating lost motion or looseness in such mechanisms.

I will describe one form of apparatus embodying my invention, and will then point out the novel features thereof in claims.

In the accompanying drawings, Fig. 1 is a view showing in vertical cross section part of a railway switch, and in front elevation one form of actuating mechanism adapted for co-operation therewith and embodying my invention. Fig. 2 is an end view of the actuating mechanism shown in Fig. 1. Fig. 3 is a top view of the actuating mechanism shown in Figs. 1 and 2. Fig. 4 is a view showing in vertical section along line IV—IV, the mechanism shown in Figs. 1, 2 and 3.

Similar reference characters refer to similar parts in each of the three views.

Referring first to Fig. 1, the reference character D designates a fixed rail of a railway switch and the reference character E designates a switch point capable of being moved into and out of engagement with said rail by longitudinal reciprocating motion of a switch rod R operably connected therewith and actuated by any convenient means. As shown in the drawings, the connection between rod R and switch point E is as follows:

Attached to two opposite faces of the switch rod R, which as shown in the drawing is of rectangular cross-section are two lugs L. These lugs are rigidly fastened in place by means of rivets 1 passing through rod R, and are provided with forward extending shoulders L' spaced from the rod and having beveled ends 4 as best shown in Fig. 3. The rod R passes through a rectangular hole in a rail foot F which is held in fixed relation with respect to rod R by means of a bolt A which passes through rod R and also through holes in the foot F as shown in Fig. 4. This foot F is provided

with a tongue F² which enters the space between rod R and shoulders L' on lugs L. The foot F is further provided with two outstanding shoulders F' having beveled edges 5. The web 7 of foot F is fastened to the switch point E by means of bolts G which pass through holes 2 provided in this web. As shown in Fig. 3 these holes are slot-shaped, thus allowing easy connection to various switch points having considerable difference in the spacing of their bolt holes.

Since manufacturing reasons make it almost impossible to secure a tight fit between foot F and rod R, and since the natural rigidity of the walls of foot F makes it difficult to secure sufficient pressure by bolt A, it is plain that some play or lost motion will result between these two members, that is, the foot F and the rod R. This is undesirable because it results in wear and looseness and consequent uncertainty of operation. In order to prevent this I insert a bolt B through holes in rod R and tongue F² of foot F, through which holes bolt B passes with considerable clearance. Two wedge-shaped members C are carried on this bolt and are so disposed that when drawn together by tightening of nut B' on bolt B a force is exerted which tends to move lugs L and foot F apart. Since lugs L are rigidly fastened to rod R the result is that foot F is moved toward the left, thus eliminating the space between bolt A and foot F and rod R. Nut B' is retained in any given position on bolt B by means of a split lock washer B².

Although I have herein shown and described only one form of apparatus embodying my invention, it is understood that various changes and modifications may be made therein within the scope of the appended claims without departing from the spirit and scope of my invention.

Having thus described my invention what I claim is:

1. In combination, a railway switch comprising a switch point, a switch foot connected therewith, a switch rod capable of reciprocating motion, lugs rigidly attached to said rod, and means interposed between said foot and said lugs for connecting the two without lost motion.

2. In combination, a railway switch comprising a switch point, a switch foot attached to said point, a switch rod capable of

reciprocating motion, a lug rigidly fastened to said rod, and a wedge for connecting said lug with said foot.

3. In combination, a railway switch comprising a switch point, a switch foot attached to said point and provided with a hole, a switch rod capable of reciprocating motion and inserted in said hole, a beveled shoulder on said foot, a lug rigidly fastened 10 to said rod and having a beveled shoulder, a bolt passing through said foot and said rod, a wedge, and means for causing said wedge to engage said beveled shoulders whereby to prevent lost motion between said 15 foot and said rod.

4. In combination, a railway switch comprising a switch point, a switch foot attached to said point and provided with an opening, a switch rod capable of reciprocating motion and inserted in said opening, 20 a beveled shoulder on said foot, a lug rigidly fastened to said rod and having a beveled shoulder, a bolt passing through said foot and said rod, a wedge and a second bolt for causing said wedge to engage said beveled shoulders whereby to prevent lost motion 25 between said foot and said rod.

In testimony whereof I affix my signature.

CHARLES J. KELLOWAY.
